UNITED STATES PATENT OFFICE.

WILHELM THEODOR UNGE, OF STOCKHOLM, SWEDEN.

PROPELLED CHARGE FOR AIR-TORPEDOES, &c.

No. 826,293.

Specification of Letters Patent.

Patented July 17, 1906.

Application filed December 10, 1903. Serial No. 184,676.

To all whom it may concern:

Be it known that I, WILHELM THEODOR UNGE, a subject of the King of Sweden and Norway, and a resident of Stockholm, Sweden, 5 have invented certain new and useful Improvements in Propelling Charges for Air-Torpedoes, &c., (for which I have applied for a patent in Sweden September 3, 1903, No. 1,661,) of which the following is a specification.

The condition for the continuous combustion after ignition of a propelling compound inclosed in an air torpedo or rocket is that the area of the discharge-opening of the torpedo or rocket should bear a certain proportion to the largest surface of combustion occurring in the propelling compound. In case of too small a discharge-opening the pressure in the gas-chamber will rise continuously until the chamber expands and bursts. The same will of course be the case if the combustion-surface should for any reason become larger than is calculated for the determined discharge-opening. Such a dangerous enlargement of the combustion-surface will take place if cracks and interstices are formed in the compound itself or between the compound and the walls of the chamber in which it is inclosed. Such interstices may be formed 20 in the propelling compound if the chamber or casing from increase of temperature expands more than the compound, if the propelling compound from decrease of temperature shrinks more than the casing, if the propelling compound has been moist when pressed into the casing and afterward has been allowed to dry, if the compound consists of compressed powder the volume of which shrinks during storage, and, finally, if 25 the air torpedo or rocket, with inclosed propelling compound, is subjected to violence or shocks during transport or in handling.

The object of my invention is to render the propelling charge of air torpedoes, rockets, and the like independent of all such circumstances which may cause cracks, &c., to be formed in the propelling charge. This is attained by making the propelling charge elastic all through and giving it the property of 30 tending to increase its volume after being packed or pressed into the chamber or casing. For this purpose the propelling charge is not packed, pressed together, or cast in one piece, but is subdivided and inclosed in a number of 35 cells with elastic walls.

The walls of the cells may be made of felt, paper, pasteboard, cloth, or other suitable elastic materials, which at the same time ought to be bad conductors of heat, and in order to prevent the absorption or release of moisture they may be impregnated by a non-volatile oil or grease.

In loading, one cell filled up and packed with the compound is introduced into the containing chamber or casing and compressed, 60 and thereafter another filled and packed cell is introduced and compressed against the foregoing cell and against the walls of the casing. In this way cell after cell is introduced and compressed until the casing is properly 65 filled up. Thus all interstices are removed, and the whole charge is thereby rendered compact, elastic, and constantly expanding. The propelling compound may consist of common rocket compound or of other self-burning mixtures or of gelatinated propelling material.

Small charges of propelling compound may comprise only a couple of cells, and in air torpedoes or rockets, in which the cells always 80 are cylindrical, the cylindrical wall of the cell may be dispensed with and only the bottom of the cells, which act as compensating disks, used.

In the accompanying drawings, Figure 1 85 shows, by way of an example, a cylindrical casing in longitudinal section loaded with an elastic charge of propelling compound contained in eleven cylindrical cells with elastic walls; and Fig. 2 shows an arrangement of 90 the casing itself in longitudinal section.

A casing consisting of a cylindrical body A is provided with a cap D and base B, the latter being provided with an aperture C for the discharge of the gas generated by the combustion of the charge which is contained in the cells E E F. These cells are made of felt or other suitable material and may be impregnated with non-volatile oil and are dimensioned after the casing A, so that after 95 being tightly packed with the propelling compound G and successively placed into the casing A and afterward pressed against the previously-inserted cell and against the walls of the casing the latter is completely filled. 100 A channel H, which may be formed by boring subsequently to the filling of the casing, extends axially through a certain number of cells, the length of the channel determining the area of ignition-surface. The separat- 105 110

ing-walls or the compensating disks E of such cells as are not perforated by the channel H are preferably provided with holes J to facilitate the extension of the combustion to those cells. The combustion of the charge may thus be effected continuously from cell to cell, or two or more cells may commence to burn simultaneously, depending on the initial length of the channel, and the same rate of combustion maintained until the whole charge is exhausted.

Where compensating disks only are used, the elasticity of the charge in a radial direction may be effected by providing the casing 15 A with an inner wall K, Fig. 2, of pasteboard, cloth, felt, varnish, or the like, and, if necessary, lining this with a tube L, of metal or other suitable material, to protect the elastic surface during the filling of the casing. 20 This wall K, with or without the tube L, may be used together with complete cells even to improve the elasticity of the charge, and by diminishing the height of the cells—i. e., increasing the number of cells in the casing, 25 and it may be by increasing the thickness of the walls of the cells—what degree of elasticity that is desired may be imparted to the propelling charge in the casing. By filling air torpedoes, rockets, and the like according to the system herein described the various parts into which the propelling charge is subdivided are rendered practically independent of each other as regards any possible variation in their volumes and also as regards the combustion of the contents of each cell, which proceeds independently of what may occur in the other cells, while at the same time the combustion of the charge as a whole is continuous and can be regulated, as 35 40 regards rate, as has been already set forth.

I claim—

1. The herein-described air torpedo, rocket or the like, comprising an outer casing provided with a cap at one end and a base at the other, a plurality of separate propelling charges, and elastic compensating disks between them, some of said charges and disks and the base having an aperture extending through them, as and for the purpose described.

2. The herein-described air-torpedo, rocket or the like, comprising an outer casing provided with a cap at one end and a base at the other, a plurality of separate propelling charges, walls of elastic material around them and elastic compensating disks be-

tween them, some of said charges and disks and the base having an aperture extending through them, as and for the purpose described.

3. The herein-described air-torpedo, rocket or the like, comprising an outer casing provided with a cap at one end and a base at the other, a plurality of separate propelling charges, and elastic compensating means between them of elastic material impregnated with non-volatile oil or grease, as and for the purpose described.

4. The herein-described air-torpedo, rocket, or the like, comprising an outer casing provided with a cap at one end and a base at the other, a plurality of separate propelling charges, walls of elastic material around them and elastic compensating disks between them, said elastic walls and disks being impregnated with non-volatile oil or grease, as and for the purpose described.

5. The herein-described air-torpedo, rocket or the like, comprising an outer casing provided with a cap at one end and a base at the other, a plurality of separate propelling charges, with elastic walls and elastic compensating disks between them, the propelling charges being compressed against each other, as and for the purpose described.

6. The herein-described air-torpedo, rocket, or the like, comprising an outer casing provided with a cap at one end and a base at the other, a plurality of separate propelling charges and an elastic envelop or cell surrounding each of said separate charges, some of said charges and the base having an aperture extending therethrough, substantially as and for the purpose described.

7. The herein-described air-torpedo, rocket or the like, comprising an outer casing provided with a cap at one end and a base at the other, a plurality of separate propelling charges, and an elastic envelop or cell consisting of a tubular body and disks at each end thereof, surrounding each of said separate charges, some of the charges and the base having an aperture extending therethrough, substantially as and for the purpose described.

In testimony whereof I have signed my name to this specification in the presence of two subscribing witnesses.

WILHELM THEODOR UNGE.
